WILLIAM P. HASKINS, OF MENDOTA, ILLINOIS.

Letters Patent No. 70,334, dated October 29, 1867.

IMPROVEMENT IN BALL-AND-SOCKET JOINT.

The Schedule referred to in these Letters Patent and making part of the same.

TO ALL WHOM IT MAY CONCERN:

Be it known that I, W. P. HASKINS, of Mendota, in the county of La Salle, and State of Illinois, have invented a new and useful Improvement in Ball-and-Socket Universal-Joint Shaft-Couplings; and I do hereby declare that the following is a full, clear, and exact description of the same, reference being had to the annexed drawings, making part of this specification, in which—

Figure 1 is a perspective view, one socket being removed.

Figure 2 is an elevation and section.

Figure 3 is a transverse section on the line $x\ x$, fig. 2.

The same letters are employed in all the figures to indicate identical parts.

My invention consists in the mode of securing the ball-and-socket joint-coupling by pins and strips of leather, so that the coupling cannot separate.

A A are the sockets, attached to the end of the respective shafts at A'. These sockets have rounded cavities to receive the ball-couplings B, their rounded heads B' being inserted in the cavities, and there fastened by pins D passing through holes C in the sockets, and through the heads B'. These pins are set at right angles to one another, so that one ball should have a free vertical play in its socket, while the other has a like horizontal play. In order to secure the pins in place, another set of holes in each ball and socket is bored at right angles to the one through which the pin passes, through which a leather or other pliable thong, E, is passed, passing also through a hole in the middle of the pin D, and keeping all the parts united.

What I claim as my invention, and desire to secure by Letters Patent, is—

1. The mode of securing the parts of a ball-and-socket joint by means of a pin passing through the socket and ball, and a thong passing through the ball and socket, and also through the pin, substantially in the manner set forth.
2. I claim the sockets A A, constructed with rounded cavities perforated by four holes, substantially as set forth.
3. In combination with sockets constructed as described, the double-headed link, substantially as set forth. In testimony whereof I have signed my name to this specification in the presence of two subscribing witnesses:

WM. P. HASKINS.
